WALL CLOCK

Lillian C. Dale, 2004 Weaver Circle,
Monroe, La. 71201

Filed Mar. 3, 1972, Ser. No. 331,799

Term of patent 14 years

Int. Cl. D10—01

U.S. Cl. D42—7 R

FIG. 1 is a front elevational view of a wall clock showing my new design;

FIG. 2 is a top plan view thereof;

FIG. 3 is a right side elevational view thereof, the left side being a mirror image thereto;

FIG. 4 is a bottom plan view thereof;

FIG. 5 is a rear elevational view thereof.

I claim:

The ornamental design for a wall clock, as shown and described.
